UNITED STATES PATENT OFFICE

154,723

DESIGN FOR A REVOLVING SIGN

William L. Stensgaard, Park Ridge, Ill., assignor
to W. L. Stensgaard and Associates, Inc., a cor-
poration of Illinois

Application July 20, 1948, Serial No. 147,676

Term of patent 14 years

(Cl. D1—12)

To all whom it may concern:

Be it known that I, William L. Stensgaard, a citizen of the United States, residing at Park Ridge, in the county of Cook and State of Illinois, have invented a new, original, and ornamental Design for a Revolving Sign, of which the following is a specification, reference being had to the accompanying drawing, forming a part thereof.

Figure 1 is a side elevational view of a revolving sign embodying my novel design;

Figure 2 is an end elevational view of the device shown in Figure 1, looking from the right of such figure; and

Figure 3 is a top plan view of said design.

I claim:

The ornamental design for a revolving sign, as shown.

WILLIAM L. STENSGAARD.
